UNITED STATES PATENT OFFICE.

JOHN B. HIPWELL, OF READING, PENNSYLVANIA, ASSIGNOR TO WINDSOR MACHINE CO., OF READING, PENNSYLVANIA, A CORPORATION OF PENNSYLVANIA.

AUTOMATIC MEASURING ATTACHMENT FOR CIRCULAR-KNITTING MACHINES.

No. 904,204.

Specification of Letters Patent. Patented Nov. 17, 1908.

Application filed September 4, 1906. Serial No. 333,064.

To all whom it may concern:

Be it known that I, JOHN B. HIPWELL, a citizen of the United States, and a resident of the city of Reading, in the county of Berks and State of Pennsylvania, have invented certain new and useful Improvements in Automatic Measuring Attachments for Circular-Knitting Machines, of which the following is a specification.

10 My invention relates to circular knitting machines adapted for the alternate rotary and reciprocating knitting commonly employed in knitting stockings, and it consists in an improved automatic measuring attachment adapted to positively measure the length of the tubular portions of a continuously produced fabric, irrespective of the number of courses required to produce the same, as fully described in connection with 20 the accompanying drawing and specifically pointed out in the claims.

Figure 1 is a partial front elevation of a knitting machine having my improvements applied thereto in preferred form. Fig. 2 is an end view of the same looking in the direction of the arrow 2, Fig. 1. Fig. 3 is an enlarged rear view, looking in the direction of the arrow 3, Fig. 2. Fig. 4 is a separate detail view showing the drive-pawl held 30 in action pending the release of the same by the pattern chain. Fig. 5 is a plan view of one of the drop weights.

The particular form of circular knitting machine which is partially indicated in the drawings in connection with my improvement, is fully described and shown in Patent No. 817,775, issued to me April 17th, 1906. The rotary cam cylinder 4, mounted in frame 5, is rotated by bevel gear 6 on the 35 pulley shaft 7; rotary or reciprocating movement thereof being changeably effected by means of tight and loose pulleys and a clutch on said shaft, and the reciprocated rack-bar 8. The pattern chain 10, carried 40 on pattern wheel 11 having a ratchet portion 12, is driven by a pawl 13 which is connected to a pivoted pawl-carrying lever 14 (Fig. 3), arranged to be swung by said reciprocating rack-bar 8. The mechanism 45 thus briefly referred to merely indicates ordinary features of a knitting machine to which my invention is applicable, such features including also suitable means, operated by properly located projections on the 50 pattern chain, for effecting the changes in the operation of the machine required for alternate rotary knitting as in the manufacture of stockings.

In my improved mechanism provision is made for holding the pawl 13 out of operative engagement with the pattern ratchet wheel 12 so as to leave the pattern mechanism at rest during ordinary rotary knitting, and for throwing it into operative engagement when the actual desired length of tubular 55 knitting (leg or foot or both) has been produced, so that the pattern chain may then effect the required changes for heel and toe knitting. For this purpose I employ, as shown, a pair of drop weights 20 and 21, adjustably secured to a drop-frame 22, which is provided at its upper end with hooked fingers 23 adapted to be attached by the operator to the depending top-edge of a stocking (see Fig. 1) preparatory to knitting 60 the leg portion. The lower drop-weight 20 is adjustably set to suit the length of leg portion required, and the upper drop-weight 21 is adjustably spaced therefrom to suit the length of foot portion required. These drop-weights are arranged to slide vertically upon a guide-rod 25 suitably fixed to a support 26, and are slotted as indicated at 45 Fig. 5 so as to pass the arm 30 of a bell-crank 65 which is pivoted to said guide-rod at 28 so that the vertical arm 29 thereof will normally project into the path of the descending weights, while the other arm 30 is connected to a parallel movable rod 31, the upper end 27 of which is connected at 32 70 to one end of a pivoted lever 33, the other end 34 of which lies under the drive-pawl 13. The weight of this movable rod 31 is preferably partly counterbalanced by a spring 35 so as to facilitate the raising of the 75 same by the action of the drop-weights upon the bell-crank; said movable rod however normally falling into lowered position so as to cause the end 34 of the pivoted lever 33 to hold the drive-pawl 13 out of engagement 80 with the pattern ratchet wheel 12 until the movable rod is raised by the descending drop-weight. This occurs after the required length of tubular leg portion has been 85 knitted, the lower drop-weight 20 then automatically operating the bell-crank to raise the movable rod, and thus permitting the constantly reciprocated drive pawl to drop 90 into operating engagement with the pattern ratchet wheel. This operating engagement 95 100 105 110

must continue until the pattern chain has effected, as usual, the required changes in the operation of the machine to produce the heel portion of the stocking. In the preferred construction shown I allow the drop-weight 20 to promptly pass the bell-crank arm 29, and provide a latch 40 arranged to hold the lever end 34 in depressed position until said latch is moved at the proper time by a projection on the pattern chain so as to release said lever end and permit it to raise the pawl out of action. The rotary knitting to form the foot of the stocking then continues until the properly spaced upper drop-weight 21 acts upon the bell-crank to again throw the pawl into action and thereby bring the pattern chain into service as before for effecting the required changes for the knitting of the toe.

It will thus be seen that with my improved attachment desired lengths of the tubular leg and foot portions of a stocking, or either, may be directly and accurately produced automatically, irrespective of the number of courses required therefor, and independently of the pattern device employed to effect the changes required in the operation of the machine for the making of the heel and toe portions. The preferred mechanism specifically described and shown may obviously be readily modified without departing from my invention.

What I claim is:—

1. In a knitting machine having a change mechanism for changing alternately to rotary and reciprocating knitting, a drop-weight measuring device arranged to automatically throw said change mechanism into operation at desired intervals without intermitting the operation of the machine.
2. In a knitting machine having a change mechanism for changing alternately to rotary and reciprocating knitting, a measuring device comprising adjustably-spaced drop-weights arranged to automatically throw said change mechanism into operation at determined intervals without intermitting the operation of the machine.
3. In a circular knitting machine, a change mechanism for changing alternately to rotary and reciprocating knitting, comprising a pattern device, driving means therefor arranged to be inoperative for rotary knitting, and a drop-weight arranged to throw said driving means into operation for reciprocating knitting at desired intervals without intermitting the operation of the machine.
4. In a circular knitting machine, a change mechanism for changing alternately to ro-

tary and reciprocating knitting comprising a pattern device, driving means therefor arranged to be inoperative for rotary knitting, a drop-weight arranged to throw said driving means into operation for reciprocating knitting, and means for throwing the same out of operation for rotary knitting at desired intervals without intermitting the operation of the machine.

5. In a circular knitting machine, a change mechanism for changing alternately to rotary and reciprocating knitting comprising a pattern device, driving means therefor arranged to be inoperative for rotary knitting, spaced-apart drop-weights arranged to successively throw said driving means into operation, and intermediately-operating means for throwing the same out of operation.

6. In a knitting machine having a change mechanism for changing alternately to rotary and reciprocating knitting, an automatic measuring mechanism comprising a drop-weight attachable to the knitted fabric, a guide-way therefor, a pivoted lever arranged in the path thereof, and controlling means between said lever and change mechanism whereby the latter is automatically thrown into operation as desired without intermitting the operation of the machine.

7. In a knitting machine having a change mechanism for changing alternately to rotary and reciprocating knitting comprising a pattern ratchet wheel and a continuously operated driving pawl therefor, an automatic measuring mechanism comprising a drop-weight attachable to the knitted fabric, and controlling means for said pawl arranged to be operated by said drop-weight for throwing the same into or out of mesh with said pattern wheel substantially as and for the purpose set forth.

8. In a knitting machine having a change mechanism for changing alternately to rotary and reciprocating knitting comprising a pattern ratchet wheel, a pattern chain and a continuously operated driving pawl therefor and a latch for said pawl, an automatic measuring mechanism comprising spaced drop-weights attachable to the knitted fabric and pawl engaging and disengaging means operated alternately by said weights and pattern chain substantially as set forth.

In testimony whereof, I affix my signature, in the presence of two witnesses.

JOHN B. HIPWELL.
